UNITED STATES PATENT OFFICE.

WILLIAM W. SLOANE, OF CHICAGO, ILLINOIS, ASSIGNOR TO GOODMAN MANUFACTURING COMPANY, OF CHICAGO, ILLINOIS, A CORPORATION OF ILLINOIS.

LOCOMOTIVE EQUALIZER.

Application filed December 8, 1923. Serial No. 679,297.

To all whom it may concern:

Be it known that I, WILLIAM W. SLOANE, a citizen of the United States, residing at Chicago, in the county of Cook and State of Illinois, have invented a new and useful Improvement in Locomotive Equalizers, of which the following is a specification.

This invention relates to improvements in locomotives or trucks and has for its principal object to provide an improved construction affording relative flexibility of the supporting wheels and axles so as to readily follow uneven track.

A usual type of construction of locomotives comprises a plurality of axles with supporting wheels thereon, said axles journaled in suitable axle boxes mounted in vertically disposed guides carried by the locomotive frame and having springs interposed 20 between each axle box and the frame. Such a construction allows the ends of an axle to move vertically a limited distance, depending upon the resiliency of the springs, thereby affording limited flexibility of movement 25 of opposite ends of the axle.

In the present invention I provide an improved and simplified construction for equalizing devices of the character above described, wherein the vertically movable 30 spring supports are mounted in guides fixed to the frame and pivotal connections are provided between such supports and the frame, comprising bell crank levers.

The invention may be best understood by 35 reference to the accompanying drawings in which:

Figure 1 is a fragmentary top plan view of one type of locomotive constructed in accordance with my invention, with parts 40 shown in section.

Figure 2 is a side view in outline of a two-axle locomotive to which my improved equalizing device is applied.

Figure 3 is a vertical cross section taken 45 on line 3—3 of Figure 1.

Figure 4 is a transverse longitudinal cross section taken on line 4—4 of Figure 3.

In the drawings a simple embodiment of my invention is shown as applied to a two-axle locomotive shown in Figure 2. A portion 50 of this locomotive is shown in Figures 1, 3 and 4, in which appear two side plates 2, 2, constituting the main portion of the frame, an axle 3 and a pair of supporting wheels 4, 4 thereof. A motor is contained 55

in a casing 5 suspended on the axle 3 to provide motive power therefor, said motor being journaled on one end on the shaft 3 and flexibly connected at the other end to the locomotive frame in any manner suitable for a 60 locomotive of the type illustrated.

Each end of each of the axles is journaled in a journal box 6 of any approved construction, said axle box being arranged to move 65 slidably between side plates 7, 7 of the usual construction.

The locomotive frame is supported on the journal boxes 6, 6 through the medium of an equalizing device constructed as follows:

A pair of rocking members 8, 8 are mounted 70 on the frame above their respective axle boxes. Each of said rocking members constitutes in effect a bell crank lever pivotally mounted to swing in a vertical plane transversely of the locomotive. The rocking members are pivotally mounted on the frame by means of two bearing pins 9, 9 supported in brackets 10, 10 carried on the side plates 2, 2 of said frame. One end of the rocking member 8, 8 comprises a lever arm 12 75 which in the form shown extends downwardly from the axis of its respective pivot pin 9, and another arm 13 extending outwardly from said pivot pin. The lower ends of the lever arms 12, 12 are connected by a 80 transverse equalizing bar 18. The outer ends of the lever arms 13 have bearing support on the upper surface 14 of a vertically movable member 15 contained between oppositely disposed guide plates 16 and 17 attached to the frame. This member is provided with a stirrup 19 at its lower end bearing on the upper ends of the supporting 85 springs 20, 20, which may be of any suitable form such as helical springs or their equivalent. These springs bear upon the upper 90 ends of the journal boxes 6, 6 in the usual manner.

In the construction shown it will be observed that the spring supporting members 15 are guided for vertical movement respective to the frame and the stirrup 19 for the springs is offset laterally so as to permit the journal boxes and springs to be widely separated thereby affording more room for the motor driving and the mechanism between the side plates. This construction also permits wide variation in the design of the locomotive. It will also be observed that the outer end of the bell crank lever arms 13, 105 110

13 is free to slide along the bearing surfaces 44, 14 of the respective spring supporting members 15, 15 during the rocking movement of the bell crank levers relative to the 5 supporting members 15, 15.

It will be seen that any vertical displacement of one end of the axle caused by uneven track will result in a corresponding displacement of the opposite end of the axle 10 in a reverse direction. The axle is thus free to swing a limited distance in a transverse plane irrespective of the resiliency of the springs.

In applying my invention to a locomotive 15 of the two-axle type shown in Figure 2, the supporting axle 3^a is preferably mounted in the usual manner, that is to say, without an equalizing device, so as to provide the desired stability to the frame, while the other 20 axle 3 is mounted as above described so as to afford a wide range of flexibility with respect to the frame and the one stabilizing axle connected therewith in the usual manner.

25 Although I have shown and described one form in which my invention may be embodied it will be understood that the construction and arrangement of the parts may be altered without departing from the scope 30 and spirit of the invention. I do not therefore wish to be understood as limiting myself to the specific construction herein disclosed, except as limited in the appended claims.

35 I claim as my invention:

1. In a car, a frame, an axle having supporting wheels, journal boxes adjacent the ends of said axle, guide means on said frame permitting limited vertical movement of 40 said journal boxes; an equalizing device comprising a pair of rocking members each pivotally mounted on said frame at oppo-

site ends of said axle, and means operably connecting said rocking members below their respective axes. 45

2. In a car, a frame, an axle movable in substantial vertical plane with respect to said frame, journal boxes adjacent the ends of said axle, guide means for said journal boxes, an equalizing device comprising a 50 pair of rocking members, means operably connecting said rocking members, a pair of vertically movable members mounted at opposite sides of said frame, one of said members having sliding engagement with one of 55 said rocking members and the oppositely disposed member having sliding engagement with the other of said rocking members, and guide means on the frame for said vertically movable members. 60

3. In a car, a frame, two laterally spaced axles movable in substantial vertical planes with respect to said frame, journal boxes adjacent the ends of said axles, guide means on said frame permitting limited vertical 65 movement of said journal boxes, an equalizing device comprising a pair of rocking members each pivotally mounted on said frame at opposite ends of one of said axles, means operably connecting said rocking 70 members, a pair of vertically movable members mounted at opposite ends of said axle and each having a bearing surface slidably coacting with one of the ends of its respective rocking member, guide means mounted 75 on said frame for each of said vertically movable members, and tension means interposed between said vertically movable members and said journal boxes.

Signed at Chicago, in the county of Cook 80 and State of Illinois, this 5th day of December, A. D. 1923.

WILLIAM W. SLOANE.
